US00D433642S

United States Patent [19]

Bauman

[11] Patent Number: Des. 433,642

[45] Date of Patent: ** Nov. 14, 2000

[54] WIRELESS ELECTRONIC COMPONENT

[75] Inventor: **Stuart P. Bauman**, Skokie, Ill.

[73] Assignee: **Shure Incorporated**, Evanston, Ill.

[**] Term: **14 Years**

[21] Appl. No.: **29/113,425**

[22] Filed: **Nov. 4, 1999**

[51] LOC (7) Cl. **10-05**

[52] U.S. Cl. **D10/104**

[57] CLAIM

An ornamental design for a wireless electronic component, as shown and described.

DESCRIPTION

FIG. 1 is a lower isometric view of the new wireless electronic component design;

FIG. 2 is an upper isometric view of the new wireless electronic component design;

FIG. 3 is a side view thereof; the other side having the same appearance;

FIG. 4 is an upper end view thereof;

FIG. 5 is a lower end view thereof;

FIG. 6 is a front view thereof; and,

FIG. 7 is a back view thereof.
